SPRING MECHANISM FOR LEAD CARRIER
OF MAGAZINE PENCILSHans Maucher, New York, N. Y., assignor to
Norma Multikolor, Inc., New York, N. Y., a cor-
poration of New York

Application October 29, 1940, Serial No. 363,252

7 Claims. (Cl. 120—14)

In practice, it has been found that lead carriers of multi-color or magazine pencils employing a single leaf spring, are unsatisfactory, due primarily to the weakness of the leaf spring, which is mounted on the carrier and exerts lateral pressure between the channel guide and the opposing inner wall of the pencil casing. For example, if while the carrier is in its advanced writing position, the pencil is accidentally dropped so that the lead strikes the floor, the force of the impact is transferred to the thumb-piece and thence to inner extremity of the leaf spring. This—especially when done repeatedly—constrains the spring towards the shank of the carrier and eventually destroys the set resiliency of the spring—thus impairing the operation of the pencil. As a matter of fact, constant use of the carrier—in complete absence of any undue jolting—frequently results in a fatigued or weak-ended spring.

I have eliminated the foregoing disadvantage by the incorporation of an auxiliary spring which absorbs the brunt of any impact or excessive wear, and materially increases the longevity of the pencil.

In the accompanying drawing,

Fig. 1 is a side elevation of the carrier and the main and auxiliary springs prior to their assembly.

Fig. 2 is a front elevation of the main spring.

Fig. 3 is a transverse section along lines 3—3 of Fig. 2.

Fig. 4 is a side elevation of the carrier assembled.

Fig. 5 is a transverse section along lines 5—5 of Fig. 4, and

Fig. 6 is an elevation of the pencil, partly in section, showing the lead carrying unit therein.

Specifically, the lead carrier comprises a tubular element 10, main leaf spring 11, and auxiliary leaf spring 12.

The tubular element has its upper extremity or shank 13 pinched together to accommodate a lead follower (not shown), and to present an open ended socket 14.

Spring 11 is relatively long and has mounted thereon a conventional thumb-piece 15. One terminal 16 of the spring is curved while the opposite terminal is formed with shoulders 17—17 and a pair of longitudinal flanges 18—18.

Upon the other hand, auxiliary spring 12 is comparatively short and virtually describes an obtuse angle with its free extremity 19, designed to contact with the main spring, as will be here-

inafter explained. The other terminal has shoulders 20—20 and a reduced tongue 21.

In assembling the carrier unit the two springs 11 and 12, as illustrated in Fig. 1, are placed in superimposed relation with tongue 21 lying in the seat between flanges 18—18 to preclude displacement, and with shoulders 17—17 and 20—20 coinciding. Together the two terminals are inserted into socket 14 down to their hilts, i. e., their respective shoulders 17—17 and 20—20. Then the socket is compressed to securely anchor the springs—see Fig. 5—whereupon they are simultaneously bent downwardly at an angle to shank 13, as shown in Fig. 4. Finally, the carrier, 15 in its entirety, is introduced into the channel guide 22 of casing 23 with thumb-piece 15 lying in slot 24. As the thumb-piece is depressed and the unit is shifted from operative to inoperative positions, or vice versa, the free end 19 of auxiliary spring 12—engaging the main spring at a point directly opposite the thumb-piece—serves to relieve the main spring from undue strain, shock or wear, and thereby bolstering the main spring and rendering it exceedingly durable and positive in action.

I claim:

1. A lead carrier for multi-color pencils having a socket at one end, a main leaf spring, an auxiliary leaf spring, corresponding terminals of said springs having shoulders, the said terminals adapted to be inserted in said socket up to said shoulders and secured therein, and an actuating device carried by said main spring.

2. A lead carrier for multi-color pencils having a socket at one end, a main leaf spring, an auxiliary leaf spring, one terminal of the main spring having a seat, the corresponding terminal of the auxiliary spring designed to rest in said seat, and the two terminals adapted to be inserted in and secured to said socket, and an actuating device carried by said main spring.

3. A lead carrier for multi-color pencils having an open end, a pair of leaf springs, corresponding extremities of the springs disposed within the open end of, and clenched together with, the carrier, and the protruding portions of said springs lying at an angle to the body of the carrier.

4. A lead carrier for multi-color pencils having an open end, a main leaf spring, a relatively short auxiliary leaf spring, corresponding extremities of the springs disposed within the open end of, and clenched together with, the carrier, and the protruding portions of said springs lying at an angle to the body of the carrier.

5. A lead carrier for multi-color pencils having at one end a main leaf spring and an auxiliary leaf spring, opposite terminals of said auxiliary spring contacting the main spring and said auxiliary spring being spaced from the main spring therebetween.

6. A lead carrier for multi-color pencils having at one end a main leaf spring and an auxiliary leaf spring, an actuating device carried by the outer side of the main spring, opposite terminals of said auxiliary spring contacting the main spring and said auxiliary spring being

spaced from the main spring therebetween, the point of engagement of one terminal of the auxiliary spring with the main spring being opposite said actuating device.

7. A lead carrier for pencils having a socket at one end, a pair of leaf springs, corresponding terminals of said springs adapted to be inserted in said socket, secured therein and bent upon themselves, and means carried by the springs for determining their extent of insertion in said socket.
